UNITED STATES PATENT OFFICE

122,785

DESIGN FOR A SIPHON OR THE LIKE

Lawrence T. Ward, Philadelphia, Pa., assignor to
Knapp-Monarch Company, St. Louis, Mo., a
corporation of Missouri

Application July 29, 1940, Serial No. 94,006

Term of patent 7 years

To all whom it may concern:

Be it known that I, Lawrence T. Ward, a citizen of the United States and a resident of Philadelphia, in the county of Philadelphia and State of Pennsylvania, have invented a new, original, and ornamental Design for a Siphon or the like, of which the following is a specification, reference being had to the accompanying drawing, forming a part thereof.

Figure 1 is a perspective view of the siphon, showing my new design;

Figure 2 is a front elevational view thereof on a reduced scale, and

Figure 3 is a side elevational view thereof on a reduced scale.

I claim:

The ornamental design for a siphon or the like substantially as shown.

LAWRENCE T. WARD.
